UNITED STATES PATENT OFFICE.

THEODORE H. WURMB AND ROBERT BAUMANN, OF ST. LOUIS, MISSOURI.

THERMOSTATIC SPRING.

No. 857,709.

Specification of Letters Patent.

Patented June 25, 1907.

Application filed December 11, 1906. Serial No. 847,379.

To all whom it may concern:

Be it known that we, THEODORE H. WURMB and ROBERT BAUMANN, citizens of the United States, and residents of St. Louis, Missouri, have invented certain new and useful Improvements in Thermostatic Springs, of which the following is a specification containing a full, clear, and exact description, reference being had to the accompanying drawings, forming a part hereof.

Our invention relates to thermostatic springs, and is an improvement on a similar device shown in our Patent No. 770,345, issued September 20, 1904.

15 In the patent above referred to, the curved metallic strips forming the spring were wound with a flat strip, or ribbon, of metal and considerable space was left between the convolutions of said strip, which arrangement materially lessened the sensitiveness of the spring, and which defect is remedied by winding the spring with a wire so as to entirely cover the same, as shown in the present application, which arrangement produces a very sensitive 25 spring.

Our present invention relates particularly to a thermostatic spring which is particularly adapted for use in fire alarm devices, and in self-recording thermometers for use in indicating abnormally high temperatures, for instance, in dry kilns, bake ovens, and other similar purposes.

While the spring herein shown and described is particularly adapted for use in devices recording abnormally high temperatures, it can be readily used in thermometers which indicate and record natural or normal temperatures. Where the spring is used in a fire or temperature alarm, certain mechanism is 35 actuated by said spring to close an electric circuit or give an alarm when the temperature rises or lowers to the degree of temperature corresponding to the set position of a pointer on the dial of the alarm device.

40 To the above purposes, our invention consists in certain novel features of construction and arrangement of parts, which will be hereinafter more fully set forth, pointed out in the claims, and illustrated in the accompanying drawings, in which:—

Figure 1 is an interior view of the housing of a fire alarm device in which our improved spring is used; Fig. 2 is a perspective view of one end of the spring, Fig. 3 being a perspective view of the opposite end of the spring;

Fig. 4 is a cross section of the spring, and showing the winding thereon.

Referring by numerals to the accompanying drawings:—1 designates the outer member of the spring, which is preferably constructed of a thin flat strip of steel, semi-circular in form, and placed immediately against the inner face of this strip 1 is a strip 2, which is similar in form and size to said strip 1, and said inner strip or liner being formed of German silver, or analogous material. Bearings 3 and 4 are rigidly fixed to the ends of the springs so formed by means of rivets 4^a, or analogous fastening devices which pass through coinciding apertures formed in the ends of the strips of the spring and through said bearings, and by means of these bearings the spring is arranged for operation in the thermometer or fire alarm housing.

5 5 designates a wire of German silver, or analogous material, which is wound upon the semi-circular spring formed by the strips 1 and 2, and the last one or two coils at each end of said wire are soldered to the top and bottom edges of the strips so as to rigidly secure the ends of the wire, and also to assist in uniting the ends of the strips 1 and 2. The wire 5 is wound upon the strips with a certain amount of tension, and, when in position, firmly presses the edges of the strips together, and the portions of said wire between the edges of the strips 1 and 2 are curved slightly outward, thus forming air spaces 6 between the outer faces of the strips 1 and 2 and the corresponding portions of said wire. 85 This arrangement provides for ventilation beneath the winding of the spring, which materially increases the sensitiveness of the spring.

It is preferable that the strip 2 and wire 5 be formed of the same material, and where German silver is made use of, the strip 2 can be cold rolled, or drawn; and by so doing, said strip becomes materially hardened. The strip and wire may be formed of different alloys with zinc as the basis of the composition, and it is essential that the material of which the strip 2 is formed be cold rolled or hardened, and the wire drawn to a certain hardness so that when the latter is wound on the two strips it will curve properly over the sides thereof.

In the drawings we have shown our improved spring as being applied to the housing of a fire alarm device, with the double bear-

ing 3 loosely mounted upon a post 7, and with the single bearing 4 pivotally connected to a swinging arm 8. This arm 8 bears upon an insulated pin 9 carried by a segment 10, which segment meshes with the teeth of the pinion 11, and the shaft of said pinion carries a pointer 12. The housing of the device may be perforated, or entirely closed and dust proof, as desired.

10 When the device as shown is set for operation, the pointer 12 is moved upon the dial to the point corresponding to the degree of temperature at which the alarm is given, and this action moves the insulated pin 9 away from the arm 8. When the temperature rises to the degree at which the pointer is set on the dial, the thermostatic spring expands, shifting the arm around so that the free end thereof contacts with the pin 9, thus closing 15 the circuit and sounding the alarm. When the temperature lowers, the spring will correspondingly contract, and the mechanical parts of the device are returned to their normal positions. Our improved form of spring 20 is very sensitive to changes of temperature and uniformly expands and contracts, and will maintain its position continuously at any fixed degree of temperature within the compass of the instrument in which it is used.

25 30 The strips forming the spring are made and the winding of the wire is done by special machinery, thereby reducing the cost and insuring uniformity in size of said springs; and the completed springs are 35 adapted for use at any point where an extremely accurate, sensitive spring is required, and particularly for use in thermo-instruments wherein abnormal temperatures are indicated and recorded.

40 We claim:—

1. A thermostatic spring, comprising two similarly curved strips, one of spring steel and the other of cold rolled German silver, and a German silver wire closely wound upon 45 said strips, in such a manner as to entirely inclose the main body portions of the curved strips.

2. A thermostatic spring, comprising two similarly curved strips, one of spring steel

and the other of cold rolled German silver, a 50 German silver wire closely wound upon said strips in such a manner as to entirely inclose the main body portions of the curved strips, the ends of which strips are rigidly united, and the ends of the wire being united to the 55 strips.

3. A thermostatic spring, comprised of two similarly curved strips, the outer one of which is formed of spring steel, the inner one being formed of zinc, alloyed with nickel, 60 copper, and antimony, and which strips are tightly wound with a wire formed of the same material as the second strip, in such a manner as to entirely inclose the main body portions of the curved strips.

4. A thermostatic spring, composed of two similarly curved strips, the outer one of spring steel, the inner one of German silver, the edges of the ends of said springs being united by solder, and a wire of German silver 70 closely wound upon said strips in such a manner as to entirely inclose the main body portions of the curved strips, and the ends of said wire being united with the ends of the strips.

5. A thermostatic spring, composed of two similarly curved strips, the outer one of spring steel, the inner one of German silver, and a German silver wire wound upon said strips in such a manner as to form air spaces 80 between the outer faces of the pair of strips and the corresponding portions of the wire.

6. A thermostatic spring, composed of two similarly curved strips, the outer one of spring steel, the inner one of alloy, and a wire 85 tightly wound upon said strips so as to entirely inclose the main body portions of the strips, which wire and the inner strip are formed of an alloy having zinc as the basis of its composition.

In testimony whereof, we have signed our names to this specification, in presence of two subscribing witnesses.

THEODORE H. WURMB.
ROBERT BAUMANN.
